END GUIDE FOR VENETIAN BLINDS

George A. Grassby, Jr., Sturgis, Mich., assignor to
Kirsch Company, Sturgis, Mich.

Application June 22, 1936, Serial No. 86,593

7 Claims. (Cl. 156—17)

This invention relates to Venetian blinds, and particularly to side guides for attachment to certain slats of the Venetian blind to keep it from swinging when a breeze strikes the blind through an open window.

It has for its objects:

First, to provide a simple, inexpensive improved side guide construction for Venetian blinds.

Second, to provide such a construction in which a sheet metal socket is provided in the end of the blind to receive a removable guiding pin which is resiliently held in the end of the slat and is removable from the slat if desired.

Third, to provide such a device which may be used satisfactorily with wooden slats and which will prevent slitting of the slat, and will eliminate unsightly connections between the guiding member and the slat.

Fourth, to provide such a device which may be suitably applied, simply and inexpensively, to metal slats with a minimum of modification of the slat.

Other objects pertaining to details and economies of the invention will definitely appear from the description to follow. The invention is defined in the claims.

A structure embodying the invention is clearly illustrated in the accompanying drawing, in which:

Fig. 1 is an elevation view of a portion of a blind showing my improved guide construction applied thereto.

Fig. 2 is a detail view partially in section showing my device applied to a slat.

Fig. 3 is a detail sectional view taken on line 3—3 of Fig. 2.

Fig. 4 is a detail sectional view taken on line 4—4 of Fig. 2.

Fig. 5 is a detail perspective view showing a modification of my invention to make it applicable to metallic slats.

Fig. 6 is a detail sectional view through a metal slat and my device applied thereto.

In the drawing 1 is a Venetian blind having a head bar 2, wooden slats 3 and lift cord 4. Along the window casing at the side of the blind I provide a track 5 consisting in this instance of a suitable hollow rod having a C-shaped cross section. Riding in this track is a shoe 6 formed to ride between the edges of the C-shaped track. A pin 7 is swiveled in an aperture 8 in the shoe. The pin has a reduced portion 9 extending through the aperture and is riveted at 10 to provide a sliding loose fit.

In the end of the wood slat I provide a slot

11 extending longitudinally thereof and opening at the end of the slat to receive the pin 7. A sheet metal member 12 having sides 13 and 14 embraces the end of the slat and is provided with an aperture 22 in register with the slot 11 for the passage of the pin 7. The members 13 and 14 extend along the sides of the slat and completely cover and conceal the slot 11. Prongs 15 are provided on these members to be driven into the wood of the slat to hold the member 12 in position.

The sides 13 and 14 at the portions thereof extending over the slot are formed as at 16 and 17 to provide a socket embracing the pin 7, and detents 18 are provided in the metal to resiliently and removably engage an annular ring 19 in the pin. It will be apparent that with this arrangement the end of the slat 3 is reinforced and a sheet metal resilient socket with inter-engaging means to engage complementary means on the pin are provided, and that by moving the slat with the guiding means thereon to the end of the track it is possible to remove the slat and the guiding means.

In Figs. 5 and 6 I show the application of my invention to an all-metal slat 103. A shoe 106 identical with the shoe 6 is provided to ride in the track such as the track 5. Pin 107 identical in all respects with the pin 7 is provided. Extending longitudinally of the metal slat is a formed groove 20 in which the pin 107 rests. Struck up from the metal of the slat and extending transversely of the groove is a band 21 to embrace the side of the pin opposite from the side embraced by the groove 20 so as to form a sheet metal socket in the end of the slat 103. A detent 118 is provided to engage the annular ring 19 in the slat.

It will be apparent that with this arrangement a sheet metal socket is formed in the end of the slat 103 to resiliently hold the pin in place, and that there is no light visible through the slat at the point of engagement with the pin.

Having thus described my invention what I claim as new and desire to secure by Letters Patent is:

1. An end guide construction for a Venetian blind comprising the combination of a track, a shoe sliding on said track, a pin swiveled on said shoe and having an annular groove thereon spaced from the shoe, a slat having a longitudinal slot therein opening at the end thereof to receive said pin, a sheet metal member fitting over the end of said slat and having sides embracing and

covering the slot, said member having an aperture at the end thereof in registration with the slot for the passage of said pin, the sides of said member being formed at the portions thereof adjacent said slot to provide a socket for said pin, and a detent formed in one of said portions to engage said annular groove on said pin whereby the pin is resiliently and detachably held in said socket.

10. 2. An end guide construction for a Venetian blind comprising the combination of a track, a shoe sliding on said track, a pin swiveled on said shoe and having an annular groove thereon spaced from the shoe, a slat having a longitudinal slot therein opening at the end thereof to receive said pin, a sheet metal member fitting over the end of said slat and having sides embracing and covering the slot, said member having an aperture at the end thereof in registration with the slot for 15 the passage of said pin, and a detent formed in one of said sides to engage said annular groove on said pin whereby the pin is resiliently and detachably held in said socket.

25. 3. In an end guide construction for a Venetian blind, the combination of a track, a shoe sliding on said track, a pin swiveled to said shoe and having an annular groove thereon spaced from said shoe, a sheet metal slat having at its end a longitudinal groove to receive said pin and having 30 a struck-up portion extending across said groove to embrace the other side of said pin resting in said groove to form a socket therefor, and a detent struck up in the metal forming said socket to engage said annular groove on the pin whereby 35 said pin is resiliently and detachably held in said socket.

4. In an end guide construction for a Venetian blind, the combination of a track, a shoe sliding

on said track, a pin swiveled to said shoe and having an annular groove thereon spaced from said shoe, a sheet metal slat having at its end a longitudinal groove to receive said pin and a band extending across said groove to embrace the other 5 side of said pin resting in said groove to form a socket therefor, and a detent in the metal forming said socket to engage said annular groove on the pin whereby said pin is resiliently and detachably held in said socket.

10. 5. In an end guide construction for a Venetian blind, the combination of a track, a shoe sliding on said track, a pin swiveled to said shoe, a sheet metal slat having at its end a longitudinal groove to receive said pin and a band extending across 15 said groove to embrace the other side of said pin resting in said groove to form a socket therefor, said pin and said socket having interengaging means whereby said pin is resiliently and detachably held in said socket.

20. 6. In an end guide construction for a Venetian blind, the combination of a track, a shoe sliding on said track, a pin swiveled to said shoe, and a sheet metal slat having at its end a longitudinal groove to receive said pin and a band extending 25 across said groove to embrace the other side of said pin resting in said groove to form a socket therefor, said pin and said socket having interengaging means.

30. 7. In an end guide construction for a Venetian blind, the combination of a track, a shoe sliding on said track, a pin swiveled to said shoe and having an annular groove thereon, a slat having a sheet metal socket at the end of and extending longitudinally of the slat, and a detent in the 35 walls of said socket resiliently engaging the annular groove on said pin.

GEORGE A. GRASSBY, JR.
